EXTRACTION PROCESS

Monroe Edward Spaght, Martinez, Calif., assignor
to Shell Development Company, San Fran-
cisco, Calif., a corporation of Delaware

No Drawing. Application April 24, 1935,
Serial No. 17,929

3 Claims. (Cl. 196—13)

This invention relates to a process for extracting mineral hydrocarbon oils which are derived from petroleum crude oils, shale oils, coal oils, etc., with selective solvents, and is particularly concerned with a process for improving the color of these oils.

It is known that mineral hydrocarbon oils generally contain several types of hydrocarbons; namely, paraffinic, naphthenic, aromatic and unsaturated constituents. In addition, other components, such as color producing substances, which may or may not be hydrocarbons, are present in smaller quantities. Of these, the paraffinic constituents are the least reactive, and their viscosity is affected the least by temperature variations. Various processes are known for concentrating paraffins or paraffinic constituents to improve the quality of lubricating oils. For example, removal of part of the non-paraffinic hydrocarbons, which lower the viscosity index of lubricating oils, by extracting the oil with a selective solvent of the sulfur dioxide type, such as sulfur dioxide or phenol, whereby non-paraffinic constituents of the oil are preferentially dissolved in the selective solvent, is a known process.

A complete or high degree of decolorization of oils by the use of these selective solvents is, however, generally impossible or possible only by using excessive amounts of the solvent, which results in a very low yield of the paraffinic oil.

I have discovered that coloring matter which naturally occurs in these mineral oils can be readily removed by extracting the oil with anhydrous or very concentrated lower aliphatic acids, either in a single-stage batch or continuous manner, or in a multiple stage or countercurrent manner. Acetic, propionic, butyric, and isobutyric acids have been found to be the most suitable for this purpose, but other liquid aliphatic acids may also be employed. With increasing molecular weight of the acids, their critical solution temperatures with oil decrease thereby, necessitating operation at lower temperatures.

By "very concentrated" aliphatic acids, I mean acids having a water content of 10% or less. Clay or a similar adsorbent material may be employed in conjunction with the aliphatic acid, if desired. I may employ any desired acid to oil ratio, depending on the temperature of operation and the quantity of coloring matter which is to be re-

moved. I have found that ratios between one part of acid to four parts of oil and four parts of acid to one part of oil to be effective in most cases, but it is understood that my invention is not limited to this range of ratios.

Low boiling aliphatic acids also have a certain selective solvent power for naphthenic, unsaturated and aromatic components of the oil, and an oil which is treated with these acids will, therefore, be improved in regard to its paraffinicity as well. However, only a small improvement in the paraffinicity is to be expected by merely treating the oils with aliphatic acids, and I prefer to treat the oils in two steps as follows: The oil is extracted in a known manner with a selective solvent of the sulfur dioxide type, producing a more paraffinic oil which is, however, not sufficiently decolorized; the paraffinic raffinate from this extraction then is treated with an aliphatic acid as described below to improve its color.

Since the second step causes a certain improvement in the paraffinicity, the first step in such a combination process may be less intensive than if it were not followed by the second step of my process. It is possible, moreover, to reverse the order of these treatments, treating the oil first with the aliphatic acid and then with a selective solvent of the sulfur dioxide type. In accordance with my invention, an oil residue or distillate which may or may not have received prior treatment with sulfuric acid, known selective solvents or other refining agents, is mixed with a desired volume of the aliphatic acid.

The volume of the solvent depends upon the quantity of the coloring matter which it is desired to remove. The oil and acid may be mixed at a temperature at which they are completely or substantially miscible, and then chilled to cause the mixture to form two liquid phases. However, I may mix the oil and the acid at the temperature at which the necessary phase separation occurs, and use no subsequent chilling. The mixture may then be allowed to remain quiescent or permitted to flow through a settling tank until there is a substantial separation into two strata. The upper layer will consist of the decolorized oil together with a small quantity of the acid, while the lower layer will contain most of the acid, coloring matter removed from the raffinate oil and a small quantity of oil. Alternatively, the mixture may be fed

directly to a centrifugal separator, or to any suitable separating device.

The two layers then are separated by decantation or in a centrifugal separator, and are treated separately to recover the aliphatic acid. Distillation at ordinary or at reduced pressure is suitable for this purpose. It is also possible to separate the acid from the oil by the addition of water. Thus, by adding sufficient water to the separated lower or heavier layer, a further separation into an oil phase and an aqueous acid phase is effected. These phases may be separated by decantation. The aliphatic acid may also be removed from the separated phases by washing them with solvents such as ethyl alcohol, acetone, etc., using methods known to those skilled in the art.

When the oil has a high content of coloring matter it may be desirable to treat the extracted oil with additional quantities of acid. This may be effected by a multiple extraction process in which fresh acid is used at each stage. I prefer, however, to use a countercurrent method of treating according to which the aliphatic acid is caused to flow countercurrently to the hydrocarbon oil, either in a multi-stage treater comprising a series of agitators or mixers and phase separating means, or by flowing the two liquids countercurrently and in contact through one or more vertical towers provided with liquid contact means, such as packing, etc.

My invention is especially applicable to the treatment of oils which have been extracted with known solvents and are suitable for use as lubricants, but which do not meet certain color or asphalt content specifications or requirements. Moreover, it is useful in the production of high grade specialty oils or white oils. The preliminary extraction may employ any selective solvent which effects a concentration of the paraffinic components of an oil without sufficiently improving the color. For convenience, I designate these solvents as solvents of the "sulfur dioxide type." The following are examples of these solvents: sulfur dioxide, furfural, quinoline, benzaldehyde, nitrobenzene, $\beta\beta'$ dichloroethyl ether, phenol and benzonitrile. Many other solvents are, however, also suitable.

My invention will be further understood from the following specific examples which are understood to be illustrative only.

Example I.—Equal parts of a sulfur dioxide extracted oil and 99.5% acetic acid were agitated, the mixture was permitted to stratify at a temperature of 20° C. and then was separated into two portions. The upper layer was distilled to remove the acid, and a raffinate having the properties given in Table I was obtained.

Table I

	Before extraction with acetic acid	After extraction with acetic acid	5
Gravity, °A. P. I.	26.2	28.9	
Visc. sec. S. U. at 100° F.	59.1	74.	
Color	2 (A. S. T. M.)	19 (Saybolt)	
Refractive index, n 20° C.	1.4945	1.4840	10
Unsulfonated residue, % by vol.	74.5	89.0	

Example II.—Separate portions of an oil extracted with sulfur dioxide and kerosene extract oil having an S. U. viscosity of 120 at 100° F. were each treated with an aliphatic acid and with adsorbent clay in the manner described above in Example I. The properties of the raffinates are shown in Table II.

Table II

Treatment	Raffinate oil properties			25
	Color	Unsulfonated residue, percent by volume	Yield, percent of feed	
None	2+(A. S. T. M.)	87	100	30
100% of 100% propionic acid + 7% clay	17 (Saybolt)	92.7	87	
100% of 100% acetic acid + 12% clay	17 (Saybolt)	92.7	88	

The treatment with aliphatic acids may be applied to oils with a wide range of viscosities and it is not to be limited to the specific oils described in the above examples. For example, my invention may be applied to oils falling within the viscosity ranges of spindle oil, machine oil, cylinder oils, etc.

I claim as my invention:

1. In the process of decolorizing lubricating raffinate obtained by extracting a viscous mineral oil with a selective solvent of the type of liquid sulfur dioxide and containing undesirable pre-formed coloring matter, the steps of extracting said raffinate with a highly concentrated lower aliphatic fatty acid under conditions to form two liquid layers and to extract from the raffinate substantially only said coloring matter, and separating said layers. 45

2. The process of claim 1 in which the fatty acid contains less than 10% water. 50

3. The process of claim 1 in which the fatty acid is selected from the group consisting of acetic, propionic, butyric and isobutyric acids. 55

MONROE EDWARD SPAHT.
